US0D1033404S

(12) **United States Design Patent** (10) **Patent No.:** **US D1,033,404 S**
Kelley et al. (45) **Date of Patent:** **** Jul. 2, 2024**

(54) **SPEAKERPHONE**

- (71) Applicant: **Hewlett-Packard Development Company, L.P.**, Spring, TX (US)
(72) Inventors: **John A. Kelley**, Santa Cruz, CA (US); **Nicholas W. Paterson**, Aptos, CA (US); **Chase Patrick Bailey**, Santa Cruz, CA (US)
(73) Assignee: **Hewlett-Packard Development Company, L.P.**, Spring, TX (US)
(**) Term: **15 Years**
(21) Appl. No.: **29/876,596**
(22) Filed: **May 24, 2023**

Primary Examiner — Messina L Smith*Assistant Examiner* — Aram Kwon(74) *Attorney, Agent, or Firm* — Quarles & Brady LLP(57) **CLAIM**

The ornamental design for a speakerphone, as shown and described.

DESCRIPTION

FIG. 1 is a perspective view of a speakerphone, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings depict portions of the speakerphone that form no part of the claimed design.
